CAMERA HOUSING FOR SURVEILLANCE SYSTEM

Robert B. Adkins, 7620 S. Wilkeson, Tacoma, Wash. 98408, and Joseph C. Byers, 12010 Densmore N., Seattle, Wash. 98115

Filed Nov. 26, 1968, Ser. No. 14,677

Term of patent 14 years

Int. Cl. D14—03

U.S. Cl. D26—14

Fig. 1.

Fig. 2.

Fig. 3.

FIG. 1 is a perspective view of a camera housing for surveillance system;

FIG. 2 is a bottom perspective view thereof; and

FIG. 3 is a side elevation thereof.

A view in the opposite direction from that illustrated in FIG. 3, indicates the overall triangular shape and shows two sides, like the side view of FIG. 3, as they come together.

The undisclosed top portion of the camera housing is substantially plain and unornamented.

We claim:

The ornamental design for a camera housing for surveillance system, substantially as shown and described.
